DESIGN FOR AN ELECTRIC FAN

Ralph E. Kruck, Springfield, Mass., assignor to
Westinghouse Electric & Manufacturing Com-
pany, a corporation of Pennsylvania

Application August 28, 1937, Serial No. 71,366

Term of patent 7 years

To all whom it may concern:

Be it known that I, Ralph E. Kruck, a citizen
of the United States, residing at Springfield, in
the county of Hampden and State of Massa-
chusetts, have invented a new, original, and or-
namental Design for an Electric Fan, of which
the following is a specification, reference being
had to the accompanying drawing, forming part
thereof, in which:

Figures 1, 2 and 3 are, respectively, views in

side, front and rear elevation showing my new
design.

The dominant features of my design reside in
the portions illustrated in the drawing in solid
black lines.

I claim:

The ornamental design for an electric fan sub-
stantially as shown and described.

RALPH E. KRUCK.
